UNITED STATES PATENT OFFICE

RANDOLPH ARBUCKLE, OF GENESEO, ILLINOIS, ASSIGNOR OF ONE-HALF TO BLANCHE M. GILBRAITH, OF GENESEO, ILLINOIS

WINDOW SCREEN

Application filed August 30, 1930. Serial No. 478,887.

This invention pertains to improvements in that type of screens shown in my Patent No. 1,715,024, issued May 28, 1929. The purpose of the present invention is to so construct a screen of the character shown in this patent that insects will not be able to see rays of light transmitted directly through the vents through which such insects are expected to pass when leaving a room and going to the outdoors; to so construct a screen of the character indicated that insects on the inside of the screen will be able to see reflected light passing from the outside through the vents inwardly and downwardly, but those outside will not be able to see light from the inside; and such further objects, advantages and capabilities as will hereafter appear and as are inherent in the construction disclosed herein. My invention further resides in the combination, construction and arrangement of parts illustrated in the accompanying drawings and, while I have shown therein what is now considered the preferred embodiment of my invention, I desire the same to be understood as illustrative only and not to be interpreted in a limiting sense.

In the drawings annexed hereto and forming a part hereof, Fig. 1 is an illustration in elevation of a window frame having a screen constructed in accordance with my invention mounted therein; Fig. 2 is a vertical section through the construction shown in Fig. 1; Fig. 2A is a vertical section of a screen having my invention applied to the upper cross bar only; Fig. 3 is an enlarged section through a rail of the screen to illustrate more clearly the construction of my present invention; Fig. 4 is a view similar to Fig. 3 of a modified form of this construction.

Referring more in detail in the annexed drawings, the window casing is denoted by the numeral 1, while the numeral 2 denotes broadly the screen mounted in the casing. This screen is shown as having a bottom cross rail 3, a middle rail 4, and a top rail 5.

In Figs. 1 and 2 I have shown the middle rail as provided with vents to permit the escape of insects, but I prefer to have these only in the top rail 5 as shown at the top of these two figures. This permits the screening material 6 to be stretched from end to end of the screen instead of being cut off as illustrated in Figs. 1 and 2. It is obvious that the screens may be constructed in either way, as may be desired by the manufacturer.

As illustrated most clearly in Fig. 1, a series of supports 7 are formed along or secured to the outward face of the frame member 5 to serve as supports for the screen material 6, keeping the same spaced away from the face 8 of the bar. Preferably a channel 9 is formed in one face of the bar, said channel having an inner portion or bottom which is parallel with the inner and outer faces of the rail. Connecting this face with the outer face is an inclined face 10 or 10a, the latter being slightly curved as illustrated in Fig. 4. The molding 11 to be used in connection with this rail has a V-shaped rib 12 which extends into the channel 9 and has an inclined face 13 which is substantially parallel to the face 10. The rib 12 extends in far enough so that no direct rays of light can pass from the outside inwardly and downwardly through the channel 9 and strike upon the face 8. All rays of light entering this channel from the outside must either strike the face 10 or the bottom face of the channel 9, while rays from inside the room will be shut out by the lower part of the rail 5, even though shining upwardly from directly below, or else, the few which pass this point are stopped by the ridge 12. The surface 13a of the molding 11a is curved slightly to correspond with the curvature of the surface 10a, but it will be recognized that the two structures shown in these two figures are clearly equivalents.

It is apparent that a channel 9 is formed by cutting a groove along one face of a bar 5 and then cutting notches in the rib left

between the channel 9 and the edge of the bar. This leaves substantially triangular projections 7 between the notches and these support not only the screen material but 5 the molding 11 or 11a. The nails by which the molding and screening are attached to the screen frame are driven through these projections 7, thus holding the molding, screening and projections tightly secured to 10 the frame bar.

In making a structure of the type illustrated in Figs. 1 and 2, wherein a vent is formed in the middle bar 4, as well as the upper bar 5, the screen may have perforations formed therein to register with the channel 9, thus permitting the insects to escape through the screen. While this would obviate the inconvenience and expense of cutting the screen into short lengths and 15 applying the same, it would on the other hand make additional expense in forming the perforations through the screen. On the whole, it is believed preferable to make the screens with the outlets at the upper end 20 only, as shown in Fig. 2A, omitting the outlet at the middle cross bar.

Having now described my invention, I claim:

1. In a screen of the character described, a 30 cross bar having a channel in the outer face thereof, supporting elements along said face and between the channel and the lower edge of the bar, a molding secured against the supporting elements and having on its inner face a rib extending into the channel to form an obstruction for rays of light between the lower edge of the bar and the upper edge of the channel.

2. In a screen of the character indicated, 40 having a cross bar provided on its outer face with a channel, said channel having its upper face inclined, said bar having a rib between said channel and the inner edge thereof, said rib being formed with vent openings for the escape of insects from inside the screen, a molding secured to the outer face of the bar and having a portion overlying the vent openings and another portion overlying the channel, the portion overlying the channel 45 having a rib formed upon its inner face to project into the channel and having its upper face inclined so that it will be substantially parallel with the inclined face of the channel.

3. A structure as defined in claim 2 in 55 which the upper face of the molding is flat.

4. A structure as defined in claim 2 in which the upper face of the molding is curved.

5. A screen comprising a frame having 60 side members and transverse members to support the screen netting, netting mounted on and secured to said frame, a cross member of the frame having a groove on the outer face thereof, the inner edge of the groove 65 cross member having projections extending

outwardly to support the netting away from the body of the cross member, and a screen holding bar secured against the netting and projections and having on its inner face a projection extending into the groove in the cross bar so as to prevent rays of light shining directly through the groove in the cross bar, between the latter and the holding bar. 70

In witness whereof, I hereunto subscribe my name to this specification.

RANDOLPH ARBUCKLE.
